CLAIM

The ornamental design for a compact mirror having pivoting frames, as shown and described.

DESCRIPTION

FIG. 1 is perspective view of a compact mirror having pivoting frames showing our new design;

FIG. 2 is a front view thereof, the rear view being identical; FIG. 3 is a top plan view of the compact mirror shown in FIG. 1;

FIG. 4 is a bottom plan view thereof;

FIG. 5 is a left side elevational view thereof, the right side elevational view being identical;

FIG. 6 is a perspective view of the compact mirror of FIG. 1 with the pivoting frames in a fully-pivoted position; and, FIG. 7 is a perspective view of the compact mirror of FIG. 1 with the pivoting frames in an open position.
